CLAIM

The ornamental design for a protecting structure for notebook computer, as shown and described.

DESCRIPTION

FIG. 1 is a perspective view of a protecting structure for notebook computer showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, showing the protecting structure for notebook computer mounted on an unclaimed computer;

FIG. 10 is a front view thereof; and,

FIG. 11 is a cross-sectional view taken along line 11-11 in FIG. 10.

The broken lines in FIGS. 9-11 illustrate environment that forms no part of the claimed design.

1 Claim, 9 Drawing Sheets
